UNITED STATES PATENT OFFICE.

LOUIS H. HAYS, OF CLEVELAND, OHIO.

MACHINE FOR CUTTING SHIRTS, BLOUSES, AND THE LIKE.

1,249,621.

Specification of Letters Patent. Patented Dec. 11, 1917.

Application filed January 2, 1913. Serial No. 739,675.

To all whom it may concern:

Be it known that I, LOUIS H. HAYS, a citizen of the United States, and a resident of Cleveland, county of Cuyahoga, and State 5 of Ohio, have invented a new and useful Improvement in Machines for Cutting Shirts, Blouses, and the like, of which the following is a specification, the principle of the invention being herein explained and the best 10 mode in which I have contemplated applying that principle, so as to distinguish it from other inventions.

In the manufacture of garments on the order, for example, of shirts, blouses and the like, it has been no small problem to accurately and uniformly cut the opening for the collar, that is, the opening to the edge of which the collar, or collar-band, as the case 15 may be, is attached in the completed garment. As such manufacture has heretofore been conducted, there is apt to be irregularity in both the sizing and location of this opening, and there furthermore always exists necessity for hand operation in trimming the edges thereof. The object, accordingly, of the present invention is the provision of a machine whereby openings of any 20 desired size may be quickly and accurately formed in such garments, and where absolute 25 uniformity in the matter of size and location of the opening may at the same time be secured without any individual attention being required thereto, or expert trimming. To the accomplishment of these and related objects, said invention, then, consists of the 30 means hereinafter fully described and particularly pointed out in the claims.

The annexed drawings and the following description set forth in detail certain mechanism embodying the invention, such disclosed means constituting, however, but one 40 of various mechanical forms in which the principle of the invention may be used.

In said annexed drawings:—

Figure 1 is a front elevation of a machine embodying my present improvements; Fig. 2 is a side elevation of the same as viewed from the left in Fig. 1; Fig. 3 is a side elevation thereof as viewed from the right in Fig. 45 1; Fig. 4 is a plan view of said machine; Fig. 5 is an enlarged elevational view of a detail; Fig. 6 is a section of such detail taken on the line 6—6, Fig. 5; Figs. 7 and 8 are respectively a longitudinal and a transverse 50 cross-section of another detail; Fig. 9 is a bottom plan view of the cutting or trimming 55

blade which forms one of the features of the machine; Fig. 10 is a section thereof taken on the line 10—10, Fig. 9; Fig. 11 is a plan view of the central portion of the table 60 whereon the garment to be trimmed is supported, showing a slight modification in construction; Fig. 12 is a diagrammatic layout of the trimming or cutting knife; Fig. 13 is a plan view of a garment, specifically a shirt, 65 shown in the position it will occupy when folded and placed on the table ready to be trimmed; Fig. 14 is a view of the same with the trimming operation completed; while Fig. 15 illustrates such garment in its unfolded condition after it has been thus 70 trimmed; Figs. 16 and 17 show another detail; and Figs. 18 and 19 show a modification.

The present improved machine is in a 75 number of respects essentially a power press, it being to the modifications and additions to the usual press structure, whereby the latter is adapted to the purpose in hand, that attention is herein directed. The operative 80 parts of the press, as well as the press bed, are supported on a suitable frame 1. Above the latter rises a pair of standards 2 joined at their upper ends and having a vertically disposed guideway formed therebetween in 85 which is reciprocably held a plunger 4 of usual construction, having a head 5 at its lower end. A crank-shaft 6, journaled in the upper ends of said standards, is connected by means of a rod 7 with such head 90 so as to thus reciprocate the same, said shaft carrying at its outer end a pulley wheel 8 which is normally loose but adapted to be thrown into engagement with the shaft to rotate the same by the operation of a clutch, 95 the detailed construction of which appears in Figs. 7 and 8.

As shown in the figures just named, the connection in question is effected by a longitudinally movable plunger 9 carried by the 100 shaft, behind which is a spring 10 that tends to throw it into engagement with a notch 11 in the hub of the pulley 8. A member 12 with an inclined face, however, is normally positioned by a spring pressed plunger 13 to 105 retain this clutch member out of engagement, but may be withdrawn, whereupon rotation of the shaft will ensue.

Such clutch mechanism is not presented as a part of the present invention, but for withdrawing the member 12 special means are provided consisting of a connecting rod 21

attached at its lower end to a lever 14 disposed beneath the press bed, as shown in Fig. 2. This lever is carried on one end of a short rock-shaft 15, to the other end of which is attached a longer lever 16 that is normally held in raised position by a tension spring 17, but is adapted to be depressed by a cross-bar 18 disposed transversely of the machine and pivotally attached near its center to said lever 16. To the respective ends of this cross-bar are attached push-rods 19 with suitable knobs 20 at their upper ends which rise above the bed of the machine. These knobs are spaced a sufficient distance from each side of the operative parts of the machine so as to insure that the operator's hands, when engaging the same, will be out of the danger zone, and particularly that they will be removed from any possibility of being caught by the trimmer blade attached to the reciprocable head 5 of the press. By reason of the construction just described it will be seen that it is necessary for both knobs 20, that is, for both ends of the cross-bar 18, to be depressed, if the lever 15 is to be rocked so as to actuate the clutch. Accordingly, the operator must use both hands before he can start the machine into operation.

30 The bed of the machine is formed with two parallel rails 22 that constitute a track upon which is movably supported the table 23 proper designed to receive the work, the general form of this table being best shown in Fig. 4. This table may be placed and secured in desired location by means of a lever 24 to the right of the standards 2, which lever is operatively connected with said table by a link 25, Fig. 2, and resiliently engages notches adjacent to an indicator or scale 26, so that any predetermined location may be given the table by simply swinging said lever until it is brought opposite the appropriate notch.

45 The general form of the table is determined by considerations that will be presently explained, it being noted that at the center of its rear edge it is cut out to allow the free up and down movement of the knife 27 carried by the press plunger or head, and that a raised strip or flange 28 extends along such rear edge, save for this opening. The knife 27 is of general curved form, as will likewise be explained in detail presently.

50 The impact of the knife, whereby the cutting of the material supported on the table is effected, is taken up by a block 29 fixedly supported on the frame 1 of the machine so as to lie in the opening in the table over which the garment being trimmed is supported by the latter. This block is preferably of wood, and over it is placed a pad 30 of paper or paper-like material which is preferably moved to present a fresh portion

60 to each succeeding blow of the knife, the

stroke of the latter, or rather the location of the block, being so gaged that the knife will just penetrate such sheet of paper, but not cut into the block.

This paper is carried on a roll 31 beneath the bed of the machine, and thence passes over a suitable guide 32 to the block 29, being carried from the latter between two feed-rolls 33 located to the rear of the standards. The detailed construction of these feed-rolls is clearly shown in Figs. 5 and 6, from which they will be seen to consist simply of two rolls, preferably of a material that will securely grip the sheet of paper, said rolls being intergeared at one end so as to rotate in opposite directions, and one thereof, the upper, being intermittently driven by a pawl 34 carried on an oscillatory arm 35 so as to engage the teeth on the corresponding gear 36. This arm 35 is connected to be oscillated from the crank-shaft 6 of the press by a rod 37 that is eccentrically secured to the end of said shaft opposite the pulley, as will be readily understood. From the foregoing it will be seen that each rotation of the crank shaft will not only effect an up-and-down movement of the plunger, and thus of the trimming knife 27 carried by the latter, but also will produce a movement of the rolls 33 which will advance the sheet 30 slightly across the block beneath the knife so as to leave a fresh portion of the latter for the next succeeding operation.

As has been indicated, the specific garment A illustrated in Figs. 13 to 15 inclusive, is a shirt, which differs from a blouse, as the two are ordinarily manufactured, by having a yoke a to connect the back portion a' and the two "fronts" a^2 , as they are called, which form the bosom of the shirt. These parts, preliminarily to the operation under consideration, are sewed together along their appropriate seams a^3 , and then the whole is folded along the central longitudinal line $z-z$ of the back, indicated on Fig. 15. Thus folded, the edges of the "fronts" will be alined and the folded garment appear as in Fig. 13. The upper corners of the "fronts" and the intervening portion of the yoke are left untrimmed, so that an opening of irregular angular form is produced as in Fig. 13, it being this opening which requires to be trimmed to form the collar. When the garment is folded in the manner described, it will be obvious that a knife having the form of half the collar opening may be employed, and still produce, when the garment is unfolded again, a perfect and symmetrical opening. Moreover, by giving such knife the proper open curve so that it will widen in a predetermined ratio to its increasing depth (see Fig. 12), different sizes of openings may be produced by simply advancing the folded garment a greater or less distance along the transverse axis of

the knife before the latter is depressed. Thus, as shown in the figure last referred to, for each of the distances, b b , b' b' , and b'' b'' representing different locations of the 5 folded garment transversely of the knife, an opening will be cut having correspondingly differing widths c c , c' c' , and c'' c'' .

So far as I am aware, it has never heretofore been deemed feasible to provide for 10 the cutting of different sizes of collar openings by a single knife, but if the trimming operation be performed with the garment folded in the particular way I have just described, this is entirely feasible, as I have 15 found by careful experiment under actual operative conditions. The exact relationship of the dimensions b b and c c , etc., is a matter of empirical determination, as will be readily understood, and it should further- 20 more be explained that there are several standards recognized in the trade for the shapes of collar openings, whether in shirts, blouses or other garments.

In order to assist in the sewing on of the collar or collar band, as the case may be, it is necessary to mark the center of the latter, and I accordingly provide means for thus marking the exact center point in the collar opening, in order that the two may later be 25 assembled in correct relation by simply bringing these marks into register. These means consist of a small knife 38 carried by the head 5 of the plunger adjacent to the right side of the curved trimming knife, as 30 viewed in Figs. 1 and 4. This knife (see Figs. 9 and 10) is mounted on a slide 39 that is tangent with the adjacent portion of the trimmer blade 27 so that such knife can be adjusted to occupy different positions and 35 thus correspond always with the location of the rear edge of the folded garment when supported on the shiftable table over the block. Adjustment of the knife is automatically effected incidentally to the shifting 40 of the table by means of an arm 40 carried thereby which engages a vertical slot in a standard 41 on the table. This slot permits the free up and down movement of the knife along with the head that carries 45 the latter, but as the table is moved in and out in adjusting the same, the knife is correspondingly shifted along the adjacent edge of the trimmer blade, to cut a V-shaped notch α at the exact center of the collar 50 opening.

Instead of the means just described for effecting adjustment of the knife 38, simultaneously with the movement of table 23, the arrangement shown in Figs. 18 and 19 55 may be utilized. In this, the lever 24 is not pivoted on a mere stud 48 (Fig. 2), but is attached to one end of a rock-shaft 49, the other end of which carries a lever 50. The latter is in turn connected with a slide 51 secured to the adjacent standard 2, said

slide projecting alongside the trimmer blade 27 and having a slot at its forward extremity that engages the arm 40, just as does the slot in the standard 41. Actuation of lever 24 will accordingly shift the knife 38 at 70 the same time that it adjusts the table, while the latter is left entirely free of any connection with the other parts of the mechanism.

To assist in properly locating the garment, when folded, on the supporting table, a guide is provided consisting of a rib 42 on a plate 43, wherewith the seam α formed between the fronts and the yoke in the case of a shirt, should be brought into alinement. 75 This seam (see Figs. 13 and 14) will incline slightly to the median line of the table and the guide rib on plate 43 will be correspondingly inclined. Such plate, however, is removable and interchangeable with another 80 plate 44, that carries ribs 45 which more nearly coincide with such median line, for use with blouses, in which there is no yoke, but simply a narrow tape or strip running from the shoulder to the collar opening of 85 the garment and therefore lying, when the garment is folded, substantially on a median line. This form of guide, for use with blouses, is shown in Fig. 11. The plates 43 and 44 carrying the guides are simply provided with pins 46 that fit in corresponding 90 openings in the top of the table, whereby such guide plates may be very readily interchanged.

In order to insure the safe retention of the 100 garment in place on the table, once it has been thus located, a clamping device is provided, the detailed construction of which is shown in Figs. 16 and 17, while its relation to the rest of the machine appears in Figs. 1 105 and 2, being omitted from Figs. 3 and 4 in order to avoid confusion. This clamping device comprises a curved spring-metal member 52, that is attached to the outer end of a rocker arm 53 so as to be disposed 110 just in front of the blade 27. The ends of this member 52 droop slightly, while its central portion is bent to fit over the guide 43 or 44 when the member is depressed to clamp the garment down on the table.

To thus depress the member, a second rocker arm 54 is provided, with a rod 55 115 connecting the same to a pedal 56. A compression spring 57 normally urges this rod upwardly, so as to retain the member in the elevated position shown in Fig. 17, while a tension spring 58 interposed between the 120 pedal and the rod provides for a resilient pressing action, and against injury to the fingers of the operator if inadvertently left beneath the member 52. The latter is of course clamped down before the trimmer 125 blade is brought down.

The general operation of the machine should scarcely require separate description.

Assuming the garment being trimmed to be a shirt, it is folded in the fashion illustrated in Fig. 13, placed on the table 23, which has been previously adjusted by operation of the lever 24 to properly locate the same with respect to the trimmer blade 27 of the press, so as to allow the latter to cut an opening of predetermined size. The garment is accurately located on the table by having its folded edges brought against the raised strips 28 along the rear edge of said table and the seam ^{as} between the yoke and the "fronts" alined with the guide 42. Thereupon the clamp member 52 is depressed and the operator, using both hands, depresses the knobs 20 and renders the clutch operative to rotate the crank shaft through one rotation, after which it is again automatically disengaged from the driving wheel. Incidentally to such rotation the sheet of paper 30 is advanced to bring a fresh portion beneath the knife preparatory to the next operation, this shifting of the sheet occurring on the upward movement of the plunger.

Not only does my improved machine constitute a very simple, safe and rapid means for trimming the collar openings in garments of the class in hand, but provision is made for the instant adjustment of the machine to cut openings of any desired size, and the accuracy of the trimming is at all times assured. Such trimming, moreover, is effected after the parts of the garment have been sewed together so that there can be no misadjustment or variation caused through carelessness, accident, or other cause, in piecing the parts together, as is at present occurring. Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In mechanism of the character described, the combination of a block; a plunger, and a trimmer blade carried thereby, reciprocable toward and from said block; and a table adapted to support a garment to be trimmed over said block, said table and blade being relatively transversely adjustable.

2. In mechanism of the character described, the combination of a block; a plunger, and a trimmer blade carried thereby, reciprocable toward and from said block; and a transversely adjustable table adapted to support the garment to be trimmed over said block.

3. In mechanism of the character described, the combination of a block; a plun-

ger, and a trimmer blade carried thereby, reciprocable toward and from said block, said blade being of open curved form; and a table adjustable along the axis of said blade and adapted to support the garment to be trimmed over said block.

4. In mechanism of the character described, the combination of a block; a plunger, and a trimmer blade carried thereby, reciprocable toward and from said block, said blade being of open curved form; a table adjustable along the transverse axis of said blade and adapted to support the garment to be trimmed over said block; and a raised flange on said table adapted to properly locate such garment with respect to said knife, when such garment is folded along its central longitudinal axis and the folded edge brought against said flange.

5. In mechanism of the character described, the combination of a block; a plunger, and a trimmer blade carried thereby, reciprocable toward and from said block, said blade being of open curved form; a table adjustable along the transverse axis of said blade and adapted to support the garment to be trimmed over said block; a raised flange on said table adapted to properly locate such garment transversely of said knife, when such garment is folded along its central longitudinal axis and the folded edge brought against said flange; and a guide substantially coinciding with the median line of said table.

6. In mechanism of the character described, the combination of a block; a plunger, and a trimmer blade carried thereby, reciprocable toward and from said block; a transversely adjustable table adapted to support the garment to be trimmed over said block; and means adapted to adjust said table transversely of said blade.

7. In mechanism of the character described, the combination of a block; a plunger, and a trimmer blade carried thereby, reciprocable toward and from said block; a transversely adjustable table adapted to support the garment to be trimmed over said block; and means consisting of a lever and link adapted to limit transverse movement of said table.

8. In mechanism of the character described, the combination of a block; a plunger, and a trimmer blade carried thereby, reciprocable toward and from said block; a transversely adjustable table adapted to support the garment to be trimmed over said block; a slotted scale; a lever moving over and adapted to contact with said scale; and a link connecting said lever to said table, said lever and link adapted to position said table in predetermined positions.

9. In mechanism of the character described, the combination of a frame; a crank-shaft journaled therein; a block; a

plunger, and a trimmer blade carried thereby, connected with said crank-shaft so as to be reciprocated toward and from said block; a sheet of paper movable across said block; 5 feed-rolls adapted to advance said sheet; and connections between said crank-shaft and feed-rolls adapted to operate the latter incidentally to the movement of said plunger away from said block.

10 10. In mechanism of the character described, the combination of a block; a plunger; a trimmer blade carried thereby, reciprocable toward and from said block; a knife mounted in said plunger adjacent said 15 trimmer blade; and a table adapted to support the garment to be trimmed over said block.

11. In mechanism of the character described, the combination of a block; a plunger; 20 a trimmer blade carried thereby, reciprocable toward and from said block; a notching knife adjustably mounted in said plunger adjacent said trimmer blade; and a table adapted to support the garment to be 25 trimmed and notched over said block.

12. In mechanism of the character described, the combination of a block; a plunger, and a trimmer blade carried thereby, reciprocable toward and from said block, 30 said blade being of open curved form; a table adjustable along the axis of said blade and adapted to support the garment to be trimmed over said block; and a knife adjustable with said table adapted to form a notch 35 in the opening cut by said trimmer blade.

13. In mechanism of the character described, the combination of a block; a plunger, and a trimmer blade carried thereby, reciprocable toward and from said block, 40 said blade being of open curved form; a table adjustable along the axis of said blade and adapted to support the garment to be trimmed over said block; a knife carried by said plunger so as to be adjustable along 45 one side of said trimmer blade, said knife being adapted to form a notch in the opening cut by said trimmer blade; and means connecting said knife with said table, whereby adjustment of the latter also adjusts said 50 knife.

14. In mechanism of the character described, a trimmer knife having an open curved form corresponding with the shape of the collar opening in a garment when the 55 latter is folded along its central longitudinal axis, the curve of said blade widening in a predetermined ratio to its depth, whereby different sizes of correctly shaped collar openings may be produced by varying the 60 position of the garment transversely of the

blade, the median line of the blade co-inciding with the central transverse axis of the folded garment.

15. In mechanism of the character described, the combination of a trimmer blade 65 having an open curved form corresponding with the shape of the collar opening in a garment when the latter is folded along its central longitudinal axis; and a knife adjacent one side of said blade adapted to form a 70 notch in the opening cut by said blade.

16. In mechanism of the character described, the combination of a trimmer blade having an open curved form corresponding with the shape of the collar opening in a 75 garment when the latter is folded along its central longitudinal axis, the curve of said blade widening in a predetermined ratio to its depth, whereby different sizes of openings may be produced by varying the position of 80 the garment transversely of the blade; and a knife adjustable along one side of said blade adapted to form a notch in the opening cut by said blade.

17. In mechanism of the character de- 85 scribed, the combination of a block; a plunger, and a trimmer blade carried thereby, reciprocable toward and from said block, said blade being of open curved form; a table adapted to support the garment to 90 be trimmed over said block; a rocker arm extending over said table adjacent to said blade; and a spring clamping member attached thereto near its mid-point and curved to correspond with said blade, said member 95 being adapted upon depression of said arm to clamp such garment onto said table.

18. In mechanism of the character described, the combination of a block; a plunger, and a trimmer blade carried thereby, 100 reciprocable toward and from said block, said blade being of open curved form; a table adapted to support the garment to be trimmed over said block; a rocker arm extending over said table adjacent to said 105 blade; and a spring clamping member attached thereto near its mid-point and curved to correspond with said blade, said member being adapted upon depression of said arm to clamp such garment onto said table, and 110 the ends of said member drooping from the point of attachment of the latter to said arm.

Signed by me, this 27th day of December, 1912.

LOUIS H. HAYS.
